Primary Examiner — Rhea Shields

(57) **CLAIM**

The ornamental design for a power adapter, as shown and described.

DESCRIPTION

FIG. 1 is a perspective view of the power adapter in accordance with the present invention;

FIG. 2 is a front side view of the embodiment of the power adapter depicted in FIG. 1;

FIG. 3 is a back side view of the embodiment of the power adapter depicted in FIG. 1;

FIG. 4 is a left side view of the embodiment of the power adapter depicted in FIG. 1;

FIG. 5 is a right side view of the embodiment of the power adapter depicted in FIG. 1;

FIG. 6 is a top side view of the embodiment of the power adapter depicted in FIG. 1; and,

FIG. 7 is a bottom side view of the embodiment of the power adapter depicted in FIG. 1.

The broken lines in the drawings are for the purpose of illustrating environment only and form no part of the claimed design.

1 Claim, 7 Drawing Sheets
